UNITED STATES. PATENT OFFICE.

DAVID J. MCALEESE AND IRVIN KNOX, OF PHILADELPHIA, PENNSYLVANIA:

DESIGN FOR A SLEEVE-HOLDER.

SPECIFICATION forming part of Design No. 30,864, dated May 23, 1899.

Application filed May 23, 1898. Serial No. 682,074. Term of patent 7 years.

To all whom it may concern:

Be it known that we, DAVID J. MCALEESE and IRVIN KNOX, residing at Philadelphia, in the county of Philadelphia and State of Pennsylvania, have invented and produced a new and useful Design for a Sleeve-Holder, of which the following is a specification.

This invention is a new and useful design for a sleeve-holder, the essential features of the design residing in certain details herein-after fully described.

Our design comprises a pear-shaped body A, gradually tapering to a point B, to which is designed a rectangular body C, having a shoulder E, from which depends a thin flat plate D. On the end of this plate D is a round concavo-convex body F, and on the lower end

of this body F are a series of laterally-extending teeth H. At the juncture of the concavo-convex body F and plate D, on either edge, we 20 design the inwardly-curved arms.

A sleeve-holder constructed in accordance with this invention has proved both useful and ornamental.

Having thus fully described our invention, 25 what we claim as new, and wish to secure by Letters Patent of the United States, is—

The herein-described design for a sleeve-holder, substantially as shown and described.

DAVID J. MCALEESE.
IRVIN KNOX.
